(57) **CLAIM**

The ornamental design for an anchoring station, as shown and described.

DESCRIPTION

FIG. 1 is top perspective view of a first embodiment of an anchoring station;

FIG. 2 is a top plan view of the anchoring station of FIG. 1;

FIG. 3 is a bottom plan view of the anchoring station of FIG. 1;

FIG. 4 is a first end view of the anchoring station of FIG. 1;

FIG. 5 is a second end view of the anchoring station of FIG. 1;

FIG. 6 is a first side view of the anchoring station of FIG. 1;

FIG. 7 is a second side view of the anchoring station of FIG. 1;

FIG. 8 is top perspective view of a second embodiment of an anchoring station;

FIG. 9 is a top plan view of the anchoring station of FIG. 8;

FIG. 10 is a bottom plan view of the anchoring station of FIG. 8;

FIG. 11 is a first end view of the anchoring station of FIG. 8;

FIG. 12 is a second end view of the anchoring station of FIG. 8;

FIG. 13 is a first side view of the anchoring station of FIG. 8;

and,

FIG. 14 is a second side view of the anchoring station of FIG. 8.

The portions shown in dashed lines in the various FIGS., including the foam padding in the first embodiment and the wheels in the second embodiment, are shown for illustration purposes and form no portion of the claimed design.
